UNITED STATES PATENT OFFICE.

JOSEPH G. HUSS, OF MINNEAPOLIS, MINNESOTA.

SOIL-PIPE VENTED FITTING.

1,052,254.

Specification of Letters Patent. Patented Feb. 4, 1913.

Application filed January 22, 1912. Serial No. 672,616.

To all whom it may concern:

Be it known that I, JOSEPH G. HUSS, a citizen of the United States, residing at Minneapolis, in the county of Hennepin and State of Minnesota, have invented certain new and useful Improvements in Soil-Pipe Vented Fittings; and I do hereby declare the following to be a full, clear, and exact description of the invention, such as will 10 enable others skilled in the art to which it appertains to make and use the same.

My invention has for its object to provide an improved sanitary fitting especially adapted for use in making closet connections 15 with the main soil stack, and also to provide a suitable vent for the closet.

To the above ends, the invention consists of the novel construction and arrangement of parts hereinafter described and defined 20 in the claims.

The improved fitting is designed to form a part of the main soil stack and is located at the floor line between the walls of a partition. Owing to the limited space in which 25 the improved fitting must be located without cutting any of the timbers of the building, I have designed, as an integrally formed entirety, a fitting consisting of a main soil pipe section, one or more closet connections, 30 and a vent pipe extension for each closet.

The invention is illustrated in the accompanying drawings, wherein like characters indicate like parts throughout the several views.

Referring to the drawings:—Figure 1 is 35 a side elevation of the improved fitting and connected parts, with a portion of the building shown in vertical section; Fig. 2 is a plan view of some of the parts shown in Fig. 1, on an enlarged scale; Fig. 3 is a vertical section taken on the irregular line $x^3 x^3$ of Fig. 2; and Fig. 4 is a horizontal section taken on the line $x^4 x^4$ of Fig. 3.

The numerals 1 and 2 indicate respectively the floor and the two walls of a partition of a building. Between the walls 2 is located a main soil stack 3, indicated, as shown in Fig. 3 by means of dotted lines. Interposed in the main soil stack 3 is the 40 vertical section 4 of the improved fitting. This section 4 forms a part of the main soil stack 3 and its lower end projects below the floor 1. Integrally formed with the intermediate portion of the section 4 is, as 45 shown, a pair of substantially horizontally extended bends 5. These bends 5 are, how-

ever, given a sufficient grade to permit a free discharge therethrough into the section 4. The outer free ends of the bends 5 extend in opposite directions and project a short distance through the two walls 2 in 60 positions to receive the discharge ends of the waste discharge of a pair of closets 6 located one on each side of the walls 2.

As is evident, the soil pipe section 4 may 65 be formed with one or more closet connections, as required. The receiving ends of the closet connections 5 are diametrically opposite one another, and are separated one from the other by means of a vertically ex- 70 tended partition 7. This partition 7 extends toward the soil pipe section 4 a distance sufficient to direct the discharge from the closet waste pipes into the soil pipe.

To add to the efficiency of a closet, it is 75 highly desirable to locate the receiving end of the vent pipe as near as possible to the closet trap. To accomplish this result, I have integrally formed with the soil pipe section 4 and the closet connections 5, a vent 80 pipe extension 8 for each closet 6. A horizontally extended partition 9 overlies the vertical partition 7 and separates the vent pipe extensions 8 from the closet connections 5. Each vent pipe extension 8 is in the 85 form of a reverse bend with its receiving end tapping the closet connection 5 adjacent to its receiving or free end. And the discharge end of each vent pipe extension 8 terminates in a hub 10 integrally formed 90 with and extending parallel to the soil pipe extension 4. Telescoped into the hubs 10 of the vent pipe extensions 8 are a pair of vent pipes 11, which at their upper ends, 95 are connected to a main vent pipe 12. In some instances, depending on the space available and the shape of the closet connection required, the receiving end of the vent pipe extension 8 may tap the closet connection 5 at its side instead of at its top, as 100 shown in the drawings.

What I claim is—

1.. A fitting constituting a part of a soil stack and having an integrally formed closet connection, and also having an integrally formed vent pipe extension in the form of a bend, the receiving end of said vent pipe extension tapping the said closet connection adjacent to its receiving end and the delivery end thereby being bent back to- 105 ward said soil stack.

2. A fitting constituting a part of a soil

stack and having an integrally formed closet connection, and also having an integrally formed vent pipe extension in the form of a bend, the receiving end of said vent pipe extension tapping the said closet connection adjacent to its receiving end, and the discharge end of said vent pipe extension being located adjacent to the soil stack, and a horizontal partition between said closet connection and the intermediate portion of said vent pipe extension.

3. A fitting constituting a part of a soil stack and having a pair of oppositely projecting integrally formed closet connections, and also having an upwardly extended vent

pipe extension for each of said closet connections, and a vertical partition between said two closet connections, and a horizontal partition overlying said vertical partition and separating said vent pipe extensions from the said closet connections, except at the receiving ends of said vent pipe extensions.

In testimony whereof I affix my signature in presence of two witnesses.

JOSEPH G. HUSS.
